COMBINED ADVERTISING SIGN AND STANDARD

Myron R. Cothorn, Greenwich, Conn., assignor to The Texas Company, New York, N.Y., a corporation of Delaware

Application February 26, 1958, Serial No. 49,805

Term of patent 14 years

(Cl. D1—12)

Fig. 1 is a front elevational view of a combined advertising sign and standard showing my new design, the rear being substantially like the front shown;

Fig. 2 is a left end elevational view thereof;

Fig. 3 is a sectional view taken on line 3—3 of Fig. 1; and

Fig. 4 is a fragmentary vertical cross section taken through the two signs of Fig. 1 along line 4—4.

I claim:

The ornamental design for a combined advertising sign and standard, as shown and described.
